CLAIM

The ornamental design for a cabinet for spools of sewing thread or the like, as shown and described.

DESCRIPTION

FIG. 1 is a perspective view of a cabinet for spools of sewing thread or the like, showing my new design; FIG. 2 is a top plan view thereof, the bottom plan view being a mirror image thereof;

FIG. 3 is a front elevational view thereof;

FIG. 4 is a rear elevational view thereof;

FIG. 5 is an elevational view of one side thereof, the opposite side being a mirror image thereof; and,

FIG. 6 is a front elevational view, comparable to FIG. 3, but with the doors in an open position to provide access to the interior of the cabinet.

FIG. 1.

FIG. 2.

FIG. 3.

FIG. 4.

FIG. 5.

FIG. 6.
